UNITED STATES PATENT OFFICE.

JOHN P. HAYES AND JOHN E. BARNHART, OF PITTSBURGH, PENNSYLVANIA.

ROTARY SNAP-SWITCH.

1,305,541.

Specification of Letters Patent. Patented June 3, 1919.

Application filed July 17, 1917, Serial No. 181,070. Renewed October 26, 1918. Serial No. 259,851.

To all whom it may concern:

Be it known that we, JOHN P. HAYES and JOHN E. BARNHART, citizens of the United States, residing at Pittsburgh, in the county 5 of Allegheny and State of Pennsylvania, have invented certain new and useful Improvements in Rotary Snap-Switches, of which the following is a specification.

Our invention relates to improvements in 10 switches and more particularly to rotary quick make and break switches carrying various elements adapted for receiving and distribution of electrical circuits.

The objects are to construct such a device 15 having a more positive action than those heretofore constructed, providing a switch in which the contacts are rotated into and out of operative connection.

Further objects are to provide a device 20 in a simple, compact and readily available form, providing ample room and capacity for attachment and connection of the various conductor elements, and to insure a quick make and break of the circuit by a 25 spring tension operative mechanism, and to be so arranged as to prevent the operator coming in contact with the conductor parts.

In the accompanying drawings, we have 30 shown a preferred arrangement and construction of a switch embodying our invention so as to give a full understanding of its construction and operation, but desire to have it understood that the arrangement and construction as shown may be varied from 35 without departing from the scope of the invention as embodied in the claims.

In the drawings:

Figure 1 is a top plan view of the switch 40 in operative connection,
Fig. 2 is a view on the line 2—2 of Fig. 1 looking in the direction of the arrows,

Fig. 3 is a sectional view of our switch 45 on the line 3—3 of Fig. 1,

Fig. 4 is a central sectional view of the 50 device, and

Figs. 5, 6 and 7 are detail views of the operating mechanism.

In the construction shown in the drawings, 55 2 represents the base of the switch made of insulating material. On the upper side of the base 2 are mounted terminal blocks 3, 3', 4, 4', 5 and 5', respectively, and

on the terminal blocks are secured clip contacts 6, 6', 7, 7', 8, 8', 9 and 9', respectively. The terminal blocks are provided with suitable binding posts 10.

Secured on the base 2 adjacent each end are suitable supporting brackets 11 adapted to carry a rotatable shaft or stem 12. The shaft 12 carries blade contacts 13, 14, 15 and 16 adapted to contact with the clip contacts 6, 6', 7, 7', 8, 8', 9 and 9', respectively. The several blade contacts may be of well known construction and are insulated from the shaft 12.

The switch is actuated by the rotary shaft 12 and an operating handle 17 through suitable gearing and quick acting mechanism, whereby to make and break the contact. The operative mechanism is mounted within or 70 upon a suitable metallic casing or bearing 18 secured to the base 2 in any manner desired and adapted to support or carry the central portion of the shaft 12.

The operating mechanism comprises a coil 75 spring 19 having its one end secured to the shaft 12 and its other end secured to a surrounding casing or drum 20 which is adapted to be rotated to tighten the tension of the spring 19 by suitable gearing operated by 80 the handle 17. Gears 22—23 are secured to the drum 20 and are adapted to mesh with gears 24 and 25 mounted on a shaft 26 journaled in the casing 18.

The operating handle 17 is pivotally 85 mounted on the shaft 26 and has suitable spring retracting mechanism 27 secured thereto. Mounted on the handle 17 is a stub shaft 28 having dog pinions 29 and 30 thereon adapted to engage the gears 24 and 25 to 90 rotate the same. Mounted in the casing or bearing 18 is a shaft 31 having other dog pinions 32 and 33 mounted thereon adapted to engage and hold the gears 24 and 25 in position.

The snap or quick make and break mechanism comprises a cam member 34 integral with or secured to the gear 23. A retaining or locking band 35 is mounted so as to surround the cam 34 and has an abutment 36 100 on its outer periphery adapted to be engaged by either of the lugs, or co-acting abutments, 37 and 38 of the casing 18. A lug 39 is formed on the band 35 and is

- adapted to be engaged within a slot 40 in a disk 41 secured on the shaft 12. The cam 34 when rotated is adapted to engage the inner periphery of the band 35 thus sliding 5 the band in such a manner that the abutment 36 will be disengaged from either the lug 37 or 38 and permit the shaft to rotate until the abutment 36 again comes in contact with one of the lugs 37 or 38.
- 10 The operation of our device will be readily understood from the above description taken in connection with the accompanying drawings, it being particularly noted that our device gives a sure snap action 15 and a positive contact at each revolution of the shaft 12.

The invention may be changed or varied in construction, arrangement or details by the skilled mechanic, or adapted to various 20 applications of use by the skilled electrician, but all such changes are to be considered within the scope of the following claims.

Having thus fully described our invention, what we claim is:—

- 25 1. A switch of the class described comprising a base, a rotary shaft carrying contacts supported on said base, a drum rotatably mounted on said shaft, a coil spring within said drum and having one end secured to said shaft and its other end to said drum; gears on said drum, an operating lever connected by other gears to said first-named gears and adapted to rotate said drum to tension said spring, a cam secured 30 to said drum and adapted to rotate therewith, a band mounted around said cam and having a projection thereon adapted to engage stationary stop members, and a locking member secured to said shaft and positively engaging a lug on said band.

- 35 2. A switch comprising a base having contact members thereon, a rotary shaft supported on said base and carrying contacts, a drum on said shaft, a coil spring having one end secured to said shaft and its other end secured to said drum, means for rotating said drum to tension said spring, a cam secured to said drum and adapted to rotate therewith, a band mounted around 40 said cam and having a projection thereon adapted to engage stationary stop members, and a locking disk member secured to said shaft and positively engaging a lug on said band.

- 45 3. A switch comprising a base of insulating material having contact members thereon, a rotary shaft supported on said base and carrying contacts, a drum rotatably mounted on said shaft, a coil spring within 50 said drum and having one end secured to said shaft and its other end to said drum, gears on said drum, an operating lever connected by other gears to said first-named gears and adapted to rotate said drum to tension said spring, and means for locking 55

said shaft in position until said spring is tensioned and automatically releasing said shaft at a predetermined point.

4. A switch comprising a base of insulating material having contact members thereon, a rotary shaft supported on said base and carrying contacts adapted to coöperate with said first-named contacts, a drum rotatably mounted on said shaft, a coil spring having one end secured to said shaft and 70 its other end secured to said drum, a supporting casing on said base surrounding said drum and supporting the central portion of said shaft, gears on said drum, a shaft journaled in said casing, gears on said shaft meshing with said first-named gears, an operating handle mounted on said last-named shaft having dog members adapted to engage said last-named gears and adapted to rotate said drum through said gears 85 to tension said spring, and means for locking said first-named shaft in position until said spring is tensioned and automatically releasing said shaft.

5. A switch comprising a base of insulating material, a rotary shaft supported on said base and carrying contacts, a drum rotatably mounted on said shaft, a coil spring having one end secured to said shaft and its other end secured to said drum, a supporting casing on said base surrounding said drum and supporting the central portion of said shaft, means for rotating said drum to tension said spring, and means for locking said shaft in position until said spring 90 is tensioned and automatically releasing said shaft, said means comprising a cam secured to said drum and adapted to rotate therewith, a band mounted around said cam and having a projection thereon adapted to 95 engage stop lugs on said casing, and means secured to said shaft and positively engaging said band.

6. A switch comprising a base of insulating material, a rotary shaft supported on 110 said base and carrying contacts, a drum rotatably mounted on said shaft, a coil spring having one end secured to said shaft and its other end secured to said drum, a supporting casing on said base surrounding said 115 drum and supporting the central portion of said shaft, means for rotating said drum to tension said spring, and means for locking said shaft in position until said spring is tensioned and automatically releasing 120 said shaft, said means comprising a cam secured to said drum and adapted to rotate therewith, a band mounted around said cam and having a projection thereon adapted to 125 engage stop lugs on said casing, and a locking disk member secured to said shaft and positively engaging a lug on said band.

7. A switch comprising a base of insulating material having contact members there- 130

- on, a rotary shaft supported on said base and carrying contacts adapted to coöperate with said first-named contacts, a drum rotatably mounted on said shaft, a coil spring 5 having one end secured to said shaft and its other end secured to said drum, a supporting casing on said base surrounding said drum and supporting the central portion of said shaft, gears on said drum, a shaft journaled in said casing, gears on said shaft meshing with said first-named gears, an operating handle mounted on said last-named shaft having dog members adapted to engage said last-named gears and adapted to 10 rotate said drum through said gears to tension said spring, and means for locking said first-named shaft in position until said spring is tensioned and automatically releasing said shaft, said means comprising a 15 cam secured to one of said first-named gears and adapted to rotate therewith, a band mounted around said cam and having a projection thereon adapted to engage stop lugs on said casing, and a locking disk member 20 secured to said shaft having means for positively engaging said band.
8. A switch comprising a base having contact members thereon, a rotary shaft supported on said base and carrying contacts, a drum on said shaft, a coil spring having one end secured to said shaft and its other end secured to said drum, gears on said drum, means for operating said gears to 25 rotate said drum and tension said spring, a cam secured to one of said gears and adapted to rotate therewith, a band mounted around said cam having a projection 30 adapted to engage stationary stops, and a locking member secured to said shaft having means for positively engaging said band.
9. A switch comprising a base of insulating material having contact members thereon, a rotary shaft supported on said base and carrying contacts, a drum mounted on said shaft, a coil spring having one end secured to said shaft and its other end to said drum, gears on said drum, an operating lever connected by other gears to said first-named gears and adapted to actuate said drum to tension said spring, and means for 35 locking said shaft in position until said spring is tensioned and automatically releasing said shaft at a predetermined point.
10. A switch comprising a base of insulating material having contact members thereon, a rotary shaft supported on said base and carrying contacts, a drum mounted on said shaft, a coil spring having one end secured to said shaft and its other end to said drum, gears on said drum, an operating lever connected by other gears to said first-named gears and adapted to actuate said drum to tension said spring, a cam secured to one of said first-named gears and adapted to rotate therewith, a band mounted around said cam having a projection thereon adapted to engage stationary stops, and a locking member secured to said shaft having means for positively engaging said band.

In testimony whereof we hereunto affix 70
our signatures.

JOHN P. HAYES.
JOHN E. BARNHART.
